UNITED STATES PATENT OFFICE

2,520,824

SPRAY GUN FOR FIRE APPARATUS
AND THE LIKEBenjamin D. Barton, Battle Creek, Mich., assignor
to American Marsh Pumps, Inc., Battle Creek,
Mich.

Application March 25, 1949, Serial No. 83,425

10 Claims. (Cl. 299—119)

1

This invention relates to improvements in a spray gun for fire apparatus and the like.

The main objects of this invention are:

First, to provide a spray gun or nozzle structure which is highly efficient for delivering so-called fog or mist and other types of spray up to substantially a stream delivery.

Second, to provide a structure which is highly efficient in producing a short or quite long range delivery of fog or mist and in a regulatable quantity.

Third, to provide a structure having these advantages which is easily controlled by the operator.

Objects relating to details and economies of the invention will appear from the description to follow. The invention is pointed out in the claims.

A preferred embodiment of the invention is illustrated in the accompanying drawings, in which:

Fig. 1 is a side elevational view of a spray gun embodying my invention.

Fig. 2 is an enlarged fragmentary view mainly in longitudinal section on a line corresponding to line 2—2 of Figs. 1 and 5 with the valve in closed position.

Fig. 3 is a fragmentary sectional view corresponding to that of Fig. 2 with the valve in fully open position.

Fig. 4 is a transverse section on a line corresponding to line 4—4 of Fig. 2.

Fig. 5 is a transverse section on a line corresponding to line 5—5 of Fig. 2.

Referring to the drawing the tubular barrel 1 is provided with a pistol type grip 2 constituting a supply conduit opening to the barrel and having a suitable hose coupling designated generally by the numeral 3. The plunger 4 is controlled by means of the trigger-like lever 5 pivoted at 6. The operating connections for the trigger or lever 5 to the plunger rod are not illustrated as they form no part of my present invention; however, suitable operating connections are illustrated in my co-pending application, Serial No. 315,547, filed June 7, 1948.

The chamber head, designated generally by the numeral 7, comprises a base or coupling portion 8 threaded upon the barrel and shouldered and externally threaded at 9 to receive the body portion 10 of the head. The head is provided with an elongated discharge port or passage 11 and a rearwardly facing valve seat 12 at the inner end of the port. The end wall 13 of the head is conical and merges into the valve seat.

2

The throat member 14 is sleeved into the head and is provided with a throat 15 of substantial width aligned with the discharge port. The throat member coacts with the end wall of the head to provide an expansion and swirl chamber 16, the front wall of the throat member being preferably conical, its rear wall 17 also preferably conical so as to provide an effective smooth guide for the water to the throat.

10 The valve 18 is provided with a stem 19 of substantial length having a socket 20 at its rear receiving the plunger rod 4. The spider-like guide member 21 is sleeved into the head and has a central bearing 22 for the valve stem. The 15 swirl producing member 23 is mounted on the valve stem this swirl producing member being of a length substantially exceeding the width of the throat 15 and having a plurality of spiral peripheral grooves 24. These grooves are of a 20 substantial pitch and extend from end to end of the swirl member. The swirl producing member is forwardly tapered.

When the valve is in seated position the larger diameter of the swirl member is within the throat 25 as is shown in Fig. 2. When the valve is in fully open or retracted position as shown in Fig. 3 the swirl member is retracted into the recess or housing 25 provided therefor in the guide member. In this position the swirl member does not 30 act on the water and the nozzle is adapted to deliver a substantially solid long range stem. The relation of the swirl member to the valve is such that the valve controls the delivery of the fog or mist-like spray created by the passage of 35 water through the throat and around the swirl member. As the tapered swirl member is retracted with the opening of a valve the character of the spray is varied owing to the taper of the swirl member and simultaneously the 40 range of delivery is varied. This enables the control of the spray not only conserving water but avoiding damage to merchandise and other objects such as is likely to result from the use of an excess of water. However, various conditions arise where a long forceful stream is desired and this can be had by fully opening the 45 valve and in which position the swirl member is retracted into the recess so that it does not effect the character of the stream.

50 The conical formation of the walls of the expansion chamber 16 described are desirable in that there are no pockets or shoulders such as might effect the character of the spray.

To further control the character of the spray 55 or stream delivered I provide an auxiliary nozzle

zle 26 which is internally threaded to engage the nipple extension 27 on the head. This auxiliary nozzle has an outwardly tapered passage 28 of substantial length terminating in a delivery port 29. This auxiliary nozzle serves to restrict the stream or spray delivered and adds to the range of delivery. It may be readily removed should occasion require.

To permit the spray gun to be used in battering an opening in a door, wall or the like the delivery end of the elongated port or passage 28 is surrounded by an outwardly spaced flange 30. The delivery end of the auxiliary nozzle passage is provided with a similar outwardly spaced flange 31. These flanges prevent the battering of the edges of the delivery ports or passages which might affect the character of the stream or spray delivered. My improved spray gun is highly efficient in the delivery of fog or mist-like spray through a very considerable range and also in delivering a full stream. This is, as pointed out, particularly useful where it is desired to avoid excessive wetting of the merchandise or the like as well as to conserve water.

Applicant's spray gun is well adapted for use in rural and other conditions where the water supply is carried in a tank or the water supply is limited.

I have illustrated and described my invention in a highly practical commercial embodiment thereof. I have not attempted to illustrate various modifications which I contemplate as it is believed that this disclosure will enable those skilled in the art to embody or adapt my invention as may be desired.

Having thus described my invention, what I claim as new and desire to secure by Letters Patent is:

1. In a structure of the class described, the combination of a barrel provided with a supply connection and with a chambered head provided with a discharge port at its outer end and with a rearwardly facing valve seat, the end wall of the chamber being conical and merging into the valve seat, a throat member disposed within said head and having a throat of substantial width aligned with said port and an outwardly facing conical wall coaxing with said end wall of said head to provide an expansion chamber, said throat member having a rearwardly facing conical fluid guide wall merging into its throat, a spider-like valve support disposed in said head at the rear of said throat member, a manually actuated plunger rod, a valve on said plunger rod coaxing with said valve seat and provided with a stem reciprocatingly mounted in said support, a forwardly tapered swirl producing member having a plurality of spiral peripheral grooves extending from end to end thereof, said swirl producing member being of a length substantially exceeding the width of the throat and being disposed on the valve stem in spaced relation to the valve and positioned relative thereto so that the larger rear portion of the swirl producing member is within the throat when the valve is closed, the valve coaxing with the discharge port to regulate the discharge from the expansion chamber during a substantial movement of the swirl producing member within the throat.

2. In a structure of the class described, the combination of a barrel provided with a supply connection and with a chambered head provided with a discharge port at its outer end and with a rearwardly facing valve seat, a

throat member disposed within said head and having a throat of substantial width aligned with said port, a spider-like valve support disposed in said head at the rear of said throat member, a manually actuated plunger rod, a valve on said plunger rod coaxing with said valve seat and provided with a stem reciprocatingly mounted in said support, a swirl producing member having a plurality of spiral peripheral grooves extending from end to end thereof, said guide member having a recess receiving said swirl member when the valve is in fully retracted position, in which position the swirl member does not effect the discharge of fluid.

3. In a structure of the class described, the combination of a barrel provided with a supply connection, a chambered head on said barrel provided with a central discharge port at its outer end and with a rearwardly facing valve seat, said head having a restricting throat of substantial width spaced rearwardly of said valve seat, there being an expansion chamber between said throat and discharge port, a valve provided with a stem reciprocatingly mounted to coax with said valve seat, a forwardly tapered swirl producing member having a plurality of spiral peripheral grooves extending from end to end thereof, said swirl producing member being of a length substantially exceeding the width of the throat and being disposed on the valve stem in spaced relation to the valve and positioned relative thereto so that the larger rear portion of the swirl producing member is within the throat when the valve is closed, the valve coaxing with the discharge port to regulate the discharge from the expansion chamber during a substantial movement of the swirl producing member within the throat.

4. In a structure of the class described, the combination of a barrel provided with a supply connection, a chambered head on said barrel provided with a central discharge port at its outer end and with a rearwardly facing valve seat, said head having a restricting throat of substantial width spaced rearwardly of said valve seat, a valve coaxing with said valve seat and provided with a stem mounted to reciprocate within said throat, a swirl producing member mounted on said stem to be reciprocated into and out of said throat and having a plurality of spiral peripheral grooves extending from end to end thereof, and a housing for said swirl member when the valve is in fully opened position.

5. A structure of the class described, comprising a barrel provided with a head portion having a discharge port at its outer end and a rearwardly facing valve seat, said head having a throat of substantial width spaced rearwardly from said valve seat and aligned therewith, a plunger rod, a valve mounted thereon to coax with said valve seat, a guide member for said valve and plunger rod, a swirl producing member having spiral peripheral grooves mounted in spaced relation to said valve so that it is within the throat when the valve is seated, the said guide member being provided with a recess into which said swirl member is retracted when the valve is fully opened.

6. In a structure of the class described, the combination with a chambered head having a discharge port at its outer end, and a rearwardly facing valve seat, said head having a restricting throat of substantial width spaced rearwardly from said valve seat there being an expansion chamber between the throat and the valve seat,

a valve reciprocatingly mounted to coact with said valve seat, a forwardly tapered swirl producing member of a length substantially exceeding the width of the throat and having a plurality of spiral peripheral grooves mounted in spaced relation to said valve to reciprocate therewith and in such relation thereto that the larger diameter of the swirl member is within the throat when the valve is seated and being fully withdrawn from the throat when the valve is in fully open position, said head being provided with a recess into which said swirl member is fully retracted when the valve is fully open.

7. In a structure of the class described, the combination with a chambered head having a discharge port at its outer end, and a rearwardly facing valve seat, said head having a restricting throat spaced rearwardly from said valve seat there being an expansion chamber between the throat and the valve seat, a valve reciprocatingly mounted to coact with said valve seat, a forwardly tapered swirl producing member having a plurality of spiral peripheral grooves mounted in spaced relation to said valve to reciprocate therewith and in such relation thereto that the larger diameter of the swirl member is within the throat when the valve is seated and being fully withdrawn from the throat when the valve is in fully open position.

8. A structure of the class described, comprising a chambered head member provided with a discharge port at its outer end, and a rearwardly facing conical valve seat, the front end wall of the head member being conical and merging into the valve seat, said head having a restricting throat of substantial width spaced rearwardly from the valve seat, a valve reciprocatingly mounted to coact with said valve seat, a forwardly tapered swirl producing member of a length substantially exceeding the width of the throat and having peripheral spiral grooves mounted in spaced relation to said valve to reciprocate therewith and coact with said throat to induce a swirling action to the liquid passing through the throat, said swirl member being fully withdrawn from the throat when the valve is fully open.

9. A structure of the class described, comprising

ing a chambered head member provided with a discharge port at its outer end, and a rearwardly facing conical valve seat, the front end wall of the head member being conical and merging into the valve seat, said head having a restricting throat spaced rearwardly from the valve seat, a valve reciprocatingly mounted to coact with said valve seat, a swirl producing member having peripheral spiral grooves mounted in spaced relation to said valve to reciprocate therewith and coact with said throat to induce a swirling action to the liquid passing through the throat, said swirl member being fully withdrawn from the throat when the valve is fully open.

10. A structure of the class described, comprising a chambered head member provided with a discharge port at its outer end, and a rearwardly facing conical valve seat, the front end wall of the head member being conical and merging into the valve seat, said head having a restricting throat spaced rearwardly from the valve seat, a valve reciprocatingly mounted to coact with said valve seat, a swirl producing member having peripheral spiral grooves mounted in spaced relation to said valve to reciprocate therewith and coact with said throat to induce a swirling action to the liquid passing through the throat, said swirl member being fully withdrawn from the throat when the valve is fully open, said head member having a swirl member guard into which the swirl member is retracted when the valve is fully open.
